PORTABLE LAWN STAND FOR A TUMBER OR THE LIKE

Maurice H. Dowding, 8950 Narrow Lake Road,
Springport, Mich. 49284

Filed Mar. 15, 1971, Ser. No. 124,625

Term of patent 14 years

Int. Cl. D6—99

U.S. Cl. D6—20

FIG. 1

FIG. 2

FIG. 4

FIG. 3

FIG. 1 is a side elevational view of a portable lawn stand for a tumbler or the like embodying my new design.

FIG. 2 is a side elevational view of the portable lawn stand for a tumbler or the like taken from a position removed 90° from that of FIG. 1.

FIG. 3 is a top view.

FIG. 4 is a cross-sectional view taken at the line IV—IV of FIG. 3, looking in the direction of the arrows.

I claim:

The ornamental design for a portable lawn stand for a tumbler or the like, substantially as shown.
